UNITED STATES PATENT OFFICE.

FRANK T. CALLEN, OF INDIANAPOLIS, INDIANA, ASSIGNOR OF ONE-THIRD TO HIMSELF, ONE-THIRD TO MILTON A. WOOLLEN, AND ONE-THIRD TO HARRY A. CALLEN, OF INDIANAPOLIS, INDIANA.

FLUSHING-VALVE.

No. 902,854.

Specification of Letters Patent.

Patented Nov. 3, 1908.

Application filed April 3, 1908. Serial No. 424,859.

To all whom it may concern:

Be it known that I, FRANK T. CALLEN, a citizen of the United States, and a resident of Indianapolis, in the county of Marion and State of Indiana, have invented certain new and useful Improvements in Flushing-Valves, of which the following, when taken in connection with the drawing and reference-letters thereon accompanying and forming a part hereof, is a full and complete description, sufficient to enable those skilled in the art to which it relates to understand, make, and use the same.

This invention relates to flushing valves used in water closets.

The object of the invention is to obtain a flushing valve of the kind named which may be quickly opened and which will slowly and automatically close.

A further object of the invention is to obtain a flushing valve of the kind named which will be simple in construction, comprising few parts, not liable to get out of order, requiring no stuffing box, and which may be adjusted to vary the time of closing.

A further object of the invention is to obtain a flushing valve which will automatically prevent dirt accumulating on the valve seat therein.

Figure 1 of the drawing is a vertical sectional view of a flushing valve embodying my invention. Fig. 2 is a sectional view on line 2—2 of Fig. 1 viewed in the direction indicated by the arrows. Fig. 3 is a vertical sectional view of radially extending valve guides on line 3—3 of Fig. 1 viewed in the direction indicated by the arrows.

A reference character applied to designate a given part is used to indicate such part throughout the several figures of the drawing wherever the same appears.

A is the shell of a flushing valve embodying this invention, *a* are external screw threads at the inlet end of the shell, *a'* are like screw threads at the outlet end of such shell, and *a''* are external screw threads on the shell arranged to engage with corresponding screw threads in cap *A'*.

B is a partition wall in shell A, by means of which the chamber C, hereinafter termed the inlet chamber, chamber D, hereinafter termed the outlet chamber and a recessed portion hereinafter termed recessed chamber D' are obtained. Communication between the inlet chamber and the outlet chamber is estab-

lished through the apertures E, E', when valves F, F', are unseated.

The flow of water into inlet chamber C, where the supply pipes thereto are of sufficient size, is through the large inlet C'; but where the water supply pipes are not large enough to obtain sufficient flow of water therethrough to properly flush the closet, a water receptacle, the lower end of which is shown in Fig. 2, lettered A'' is attached to shell A as by means of screw threads *a*, *a*, and the water flowing into and through the inlet chamber and also into and out from the water receptacle A'' is admitted through the smaller inlet C''. When the inlet C'' is not in use it is, of course, closed by an ordinary plug.

f, is the stem of valve F, and *f'* is an annular groove in such stem.

G is a disk at one end of stem *f*.

H, *H*, are radially extending guides integral with valve stem *f* and arranged to form a spider between valves F, F'. Valve F' is of slightly greater diameter than valve F, and is secured in position at the end of the spider, as by means of the bolt I. The guides *H*, *H*, are provided with concave faces *h*, on one side, forming the front thereof, and with convex faces *h'*, on the other side, forming the back thereof. When water flows from the inlet chamber C through apertures E, E', into the outlet chamber D, rotation of the valves F, F', stem *f*, and disk *G*, is obtained; the curving, as described, of the faces *h*, *h'*, of guides *H*, *H*, materially assisting to obtain such rotation.

J, is a chamber located in recessed chamber D', between the cap A', and the disk *G*.

K, is a passageway in stem *f*, communicating at one end with the chamber *J*, and at the other end with the recessed chamber D'. Passageway *K*, is adjustably restricted by adjusting screw *L*.

The mechanism for opening the valves F, F', comprises the shaft M, weighted handle N, and fingers O. The fingers are, preferably, integral (see Fig. 2) with shaft M. The fingers O are arranged to engage with the annular groove *f'* of shaft *f*, so that the rocking of the shaft M, by the raising of the handle N into substantially the position illustrated in Fig. 1 will unseat the valves F, F', as is shown in Fig. 1.

P, is a disk integral with shaft M and provided with the seating face *p*, which is ar-

ranged to form a valve to seat on face q of guide Q . Face q forms a valve seat.

R is a spring washer and S are nuts on the screw threaded end m of shaft M .

5 Guide Q , is secured to shell A by means of screw threads q' arranged to fit into corresponding screw threads in shell A , (see Fig. 2).

10 Shaft M , is provided with a number of straight sides or faces m' , and the handle N , is provided with a hole having corresponding faces arranged to fit over such shaft to rigidly attach the handle to the shaft, so that turning such handle will turn the shaft.

15 Spring washer R , interposed between handle N and nuts S , maintain the seating or valve face p' , of disk P , in contact with face or valve seat q of guide Q , so that no stuffing box is required.

20 When the valves F , F' are unseated and handle N is released the weight thereof tends to move the stem longitudinally and close such valves.

25 The longitudinal movement of stem f increases the size of chamber J , and such longitudinal movement of the stem is therefore retarded by the reduced pressure thereby created in such chamber J , and when the valves are seated, the larger area of valve F' 30 tends to hold the valves closely on their respective seats, preventing leakage there-through, and the curving of the guides H , H , produces rotation of the valves which tends to remove (at about the time of the seating 35 of the valves to close the apertures E , E'), any sediment thereon.

Having thus described my invention, what I claim as new and desire to secure by Letters Patent is,—

40 1. The combination of a shell provided with partition walls arranged to form an inlet chamber and an outlet chamber, such partitions, provided with apertures there-through of different diameter, a longitudinally movable stem, valves on the stem arranged to control the apertures, a disk on the stem arranged to form the movable wall of an air chamber in the shell, a passage way through the stem and disk arranged to communicate with the air chamber, means disposed transversely of the length of the stem to adjustably restrict the passage way, radially extending guides on the stem between the valves, such guides provided with 45 concave and convex sides respectively, and a rocking shaft and means rigid with the shaft engaging said stem to move the stem longitudinally and means to automatically return such stem to its initial position: substantially as described.

50 2. The combination of a shell provided with partition walls arranged to form an inlet chamber, an outlet chamber and a recessed chamber to one side of the inlet and

outlet chambers, a plurality of inlets to the inlet chamber, an outlet to the outlet chamber and an open end to the recessed chamber, with the partition between the inlet and outlet chambers provided with apertures of different diameters and valve seats to such apertures, a cap arranged to cover the open end of the recessed chamber, a valve stem, a disk on the stem arranged to form the movable wall of an air chamber located at one end of the recessed chamber, a passage way through the stem arranged to communicate with the air chamber, means to restrict the passage way, valves on the stem arranged to coact with the valve seats, the larger of such valves removably attached to the stem, radially extending guides on the stem and between the valves and such stem provided with an annular groove, a rocking shaft, a weighted handle to such rocking shaft outside the shell and fingers to such rocking shaft within the shell, such fingers arranged to engage with the annular groove on the stem, and means to prevent the flow of water from the shell around the rocking shaft: substantially as described.

55 3. The combination with a shell provided with partition walls arranged to form an inlet chamber, an outlet chamber and a recessed chamber to one side of the inlet and outlet chambers and such partition walls provided with apertures of different diameters, with valve seats to such apertures, and such shell provided with a plurality of inlets to the inlet chamber, of a valve stem, valves on the stem arranged to coact with the valve seats, the larger of such valves removably attached to the stem, a disk on the stem, such disk arranged to form the movable wall of an air chamber, a restricted passage way communicating with the air chamber and with the recessed chamber, radially extending guides on the stem between the valves, such guides provided with concave and convex faces, and such stem provided with an annular groove, a rocking shaft, a bearing to the rocking shaft, such bearing removably attached to the shell and provided with a valve seat at the inner end thereof, a handle on the shaft outside the shell and fingers on the shaft inside the shell, such fingers arranged to engage with the annular groove on the stem, and a disk on the rocking shaft provided with a valve on one side thereof arranged to coact with the valve seat on the inner end of the rocking shaft bearing: substantially as described.
